IMPROVEMENT IN COTTON GINS.

F. M. McMEEKIN, OF MORRISON'S MILLS, FLORIDA.

Letters Patent No. 60,402, dated December 11, 1866.

The Schedule referred to in these Letters Patent and making part of the same.

TO ALL WHOM IT MAY CONCERN:

Be it known that I, F. M. McMEEKIN, of Morrison's Mills, in the county of Alachua, and State of Florida, have invented a new and improved Cotton Gin; and I do hereby declare that the following is a full, clear, and exact description thereof, which will enable others skilled in the art to make and use the same, reference being had to the accompanying drawings, forming a part of this specification, in which—

Figure 1 is a side view of my invention.

Figure 2, a transverse vertical section of the same, taken in the line $x x$, fig. 1.

Figure 3, a plan or top view of a portion of the same.

Similar letters of reference indicate like parts.

This invention relates to a new and useful improvement in the class of cotton gins in which rollers are employed for separating the lint or fibre from the seed, and which are commonly termed "roller gins," and has for its object the thorough and rapid separation of the lint or fibre from the seed without injuring or breaking the former.

A represents a frame which may be constructed in any proper manner to support the working parts of the machine, and B is a driving-shaft placed in the lower part of frame A. C is a roller placed in the upper part of the frame A, and covered with leather or other similar material, and D is a metallic roller quite small in diameter compared with roller C, and placed above it. This metallic roller, D, is held in proper contact with roller C by means of the bearings formed of bars $a a$, which extend up through a bar, b, on the frame A, and are connected at their upper ends to a cross-bar, c, through which a screw-rod, d, attached to the bar b passes, and has a nut, e, on its upper end. By turning this nut, e, the upper roller D may be made to bear more or less hard upon roller C, as desired, and in all cases be prevented from springing out from the roller C, a contingency of frequent occurrence with the roller gin, in consequence of the necessary smallness of the diameter of one, if not of both of the rollers. E represents a plate which is attached by screws, f, to the bar b, said screws passing through oblong slots, g, in the plate E, to admit of the adjustment of the same higher or lower, as may be desired. This plate E has an inclined position, as shown in fig. 2, its lower edge being within a short distance of the periphery of roller C. F is a reciprocating rake which is composed of a series of teeth, h, secured in one side of a reciprocating frame, G, on the top of the frame A. The ends of the teeth h are nearly in contact with the periphery of the roller C, and they are curved consecutively in reverse directions, every alternate tooth being curved in the same direction, as shown in fig. 3. The roller C is rotated by a belt, i, from the shaft B, and the small metallic roller, D, is rotated by a belt, j, from the same shaft. The rake F has motion given it by a pitman, k, connected to a crank, l, on a shaft, H, which is rotated by a belt, m, from the shaft B. The cotton is fed to the device over the rake F, and the lint or fibre passes between the roller C and the lower edge of the plate E, between the rollers C and D, said rollers drawing the lint or fibre between them while the plate E prevents the seed from passing to said rollers. The rake F, on account of its reciprocating motion, ripples or detaches the seed from the cotton, the teeth h, on account of their curvature, operating upon the lint or fibre in the most favorable manner without breaking or injuring it in the least. I is a brush which strips the cotton from the discharge side of the roller C.

Having thus described my invention, what I claim as new, and desire to secure by Letters Patent, is—

The combination of the roller C, roller D, with adjustable bearings, slotted plate E, reciprocating rake G, and teeth F, as described, and brush I, arranged and operating substantially as and for the purpose specified.

The above specification of my invention signed by me this 18th day of June, 1866.

F. M. McMEEKIN.
